APPARATUS FOR TURNING STOCKINGS
AND THE LIKE

Frank Andrew Landucci, London, and Edwin Ivan Rusted, Wolvey Villa, near Hinckley, England, assignors to The Charnwood Engineering Company Limited, London, England

Application July 25, 1950, Serial No. 175,714

13 Claims. (Cl. 223—40)

1

This invention concerns apparatus for turning stockings and other tubular articles of flexible material inside out, it being explained that in the manufacture and processing of stockings and other knitted articles of footwear, the necessity arises of turning these articles inside out and vice versa; similarly in the manufacture of belts, scarves, ties and similar tubular articles it is necessary after seaming to turn these articles to bring the raw edges of the material to the inside; operations which hitherto have usually been accomplished by hand. The object of the present invention is a construction of apparatus by which such operations are effected automatically.

The invention provides apparatus for turning tubular articles inside out, comprising a female receiving member arranged to have the article passed over it so that the said member is then at least partly contained within the tubular article, means for moving the receiving member between a loading station at which it is presented to have the article passed over it and a turning station at which it presents the article for turning, turning means operable at the turning station to engage the article presented to it by the receiving member and by relative movement (i. e. relative movement as between the turning means and the receiving member) to force the article through said member and thereby to turn it inside out, and means for producing relative article turning movements between the receiving member and the turning means each time the former is presented at the turning station. The turning means may push the article at least partly through the receiving member, or pull it through, or may operate by a combination of these movements. Conveniently it comprises a rammer movable into the receiving member. It will, therefore, be seen that this apparatus permits of the turning operation being effected automatically, the only hand operation necessary being that of passing the tubular article, such as a stocking, over the receiving member. Desirably there is a plurality of the receiving members and mechanism for moving them successively to each of the two stations in turn. Thus the receiving members are presented one after another at the loading station to have the stockings or the like put on to them, and as soon as each receiving member is loaded, it is transported to the turning station. Thus a circulation is carried on between the two stations. There may be conveyor apparatus for the receiving members comprising two carrier members rotatable in spaced planes

2

about parallel axes, and a plurality of links connecting the two members at angularly-spaced locations; the length of which links is equal to the spacing between the axes and which links have the receiving members mounted on them. Advantageously the receiving members are disposed on the links with their axes substantially parallel to a plane containing the axes of rotation.

10 10 The receiving member, or each of them, is preferably in the form of a tube open at each end. It may, however be in the form of a ring together with a suitable support or supports.

In that embodiment of the apparatus in which there is a plurality of the receiving members, the mechanism for moving them is preferably so constructed as to move them intermittently, permitting each of them in turn to pause first at the loading station and subsequently at the turning station. This mechanism may comprise a Geneva mechanism.

The foregoing and other features of the invention defined in the appended claims are incorporated in the stocking turning apparatus which will now be described, as an example, with reference to the appended drawings, in which—

Figure 1 is a side elevation of the mechanism; Figure 2 is a front elevation thereof; Figure 3 is an elevation of the Geneva mechanism and

Figure 4 is a section thereof taken on the line IV—IV in Figure 3;

Figure 5 is a perspective view, partly in broken section, of the Geneva mechanism, spiders, and stocking-receiving tubes hereinafter described;

Figure 6 is an elevation, and Figure 7 a sectional view, of the lazy-tongs mechanism;

Figure 8 is a view of a gripper-carrying arm hereinafter described, while

Figure 9 is a plan and

Figure 10 is an elevation of the lower part thereof, including the grippers.

This apparatus comprises a plurality of stocking-receiving tubes 1a, 1b, 1c and 1d and conveyor apparatus for moving the tubes in succession from a loading station to a turning station. The loading station is that occupied by the tube 1a in Figs. 1 and 5, the turning station being that occupied by tube 1c. Preferably there are two spiders, 2, 3, mounted to rotate on a machine frame 10 about horizontal axes 4, 5, one axis above the other, the planes of rotation being slightly spaced apart. The spiders have an equal number of arms, shown at 2a—2d and 3a—3d. Each arm of one spider is connected to

the corresponding arm of the other spider by a link (the links being respectively numbered 6a-6d), and each link carries a bracket (7a-7d) on which an open-ended stocking-receiving tube 1a-1d is disposed, substantially vertically. The distance between the axes 4, 5 is equal to the length of each link 6a-6d, and the arrangement is therefore such that as the two spiders rotate the tubes 1a-1d are caused to travel in a substantially circular path, while each maintains its substantially vertical attitude (i. e. the axes of the tubes are substantially parallel to a plane containing the axes 4, 5). The spiders 2, 3 are driven through a Geneva mechanism so that they move step by step. Each tube is in turn presented at a loading station at one side of the machine where it is accessibly positioned so that an operator may draw the stocking on to it, the toe part of the stocking being then located at the top end of the tube. Thence the loaded tube 20 travels (either directly or with one or more pauses, depending on the ratio of the Geneva mechanism) through approximately 180 degrees of its path to a turning station at which it is again presented substantially vertically. At this 25 turning station there operates a turner which consists of a plunger or ram rod 8 movable in a substantially vertical path in such manner that in its descent it engages the toe end of the stocking and forces the stocking down through the tube until the toe is presented at the bottom of the tube. It may readily be appreciated that in this operation the stocking, or at least part of it which is carried by the plunger 8 down through the tube, is turned inside out.

The Geneva mechanism is carried in a casing 9 on the machine frame 10 and is best shown in Figs. 3 and 4. It is of conventional character and comprises a constantly-rotating pin disc 11 carrying a pin 12 capable of entering radial slots 13 in a star disc 14 which is rotated step by step about axis 5 and is connected to spider 3. The pin disc 11 is driven from motor 15 through clutch mechanism or stop start mechanism 16 controlled by pedal 17, belt 18, infinitely variable 45 change-speed bearing 19, belt 20, and belt pulley 21 on a flywheel 22 secured to the shaft 23 of the pin disc 11. The gearing 19 permits the speed of the machine to be adjusted to match the dexterity of the operator in loading stockings or the like onto the tubes. By operation of control 17, or of a stop-start push button controlling the electric motor 15 or its clutch, the operator can readily cause the apparatus to come to a standstill or cause any receiving member to pause between the loading and turning station. There may be a brake (e. g. an electro-magnetic brake) which is automatically applied when the clutch is released or when the motor is de-energised, so that the moving parts are rapidly brought to a standstill.

The plunger 8 is reciprocated by a suitable mechanism in time with the movements of the tubes, so that it descends each time a tube is presented at the turning station, and ascends before that tube moves on to the loading station. Since the travel of the plunger 8 is substantial, it is desirably moved through a lazy tong mechanism 24 for thereby a comparatively small initial movement of one end of the tongs (such as may readily be derived from a crank, cam or eccentric) produces a much greater movement of the other end of the tongs, to which other end the plunger 8 is connected. Suitable guides are provided for ensuring that the plunger movement is

rectilinear so that the plunger maintains its alignment with the tube.

Specifically, the plunger 8 is attached at its upper end to a slide block 25 slidable in guide 26, and slides through a guide block 27 fixed at the lower end of the guides. The top end of the lazy tong mechanism 24 is pivoted at 28 to a part 30 on the plunger 8, and its bottom end is pivoted at 29 to the machine frame, while the two lowermost links 24a, 24b of the mechanism are connected by toggles 31a, 31b to a connecting rod 32 mounted on a crank pin 33 on the pin disc 11.

It will be appreciated that in order to avoid damage to the stockings or the like, each tube 1a-1d should have its upper lip of smooth rounded form, and that all parts with which the stockings are likely to come in contact should be smooth and void of any such excrescences as are liable to cause snags. Likewise the plunger 8 should be smooth and its tip 8' rounded.

While it is within the scope of the invention to impart to the plunger an amplitude of stroke adequate to ensure that its descent through each tube will discharge the turned stocking or the like from the lower end of the tube, yet in order to keep the amplitude of stroke and the length of the tube at a minimum it is preferred to provide extracting mechanism which grasps the toe part of the stocking, as it is pushed clear of the lower end of the tube by the plunger, and subsequently pulls the stocking through the tube. For this purpose there is a pendulous arm 34 pivoted at 35 on the machine frame and carrying a gripper 36 at its bottom end and this arm is so disposed and mounted and is so swung in step with movements of the plunger that each time the plunger pushes the stocking down a tube, the gripper is placed to receive the toe of the stocking, grips it, and then retires. In this retiring movement the stocking is drawn out of the bottom end of the tube and is carried away. At an appropriate stage the gripper 36 is opened to release the stocking. The released stocking may fall into a suitable receptacle or in the retiring movement the stocking may be laid across a receptacle or tray 37 and then released by the gripper 36.

In the illustrated construction, the arm 34 is rocked by means of a link 38 connected to a lever 39 on a rock shaft 40, which latter also carries a truck lever 41 acted on by a cam 42 on fly-wheel 22. In order to adjust the travel of the gripper 36 to that which is best having regard to the length of the stockings or the like on which the machine is, for the time being, to operate the point at which the link 38 is hinged to arm 34 is adjustable along a curved slot 43 towards and away from the pivot 35 and may be clamped in the desired position by screw-and-nut clamping mechanism 44.

The gripper 36 is carried by a carrier 45 on the bottom end of arm 34, and in order to ensure that in its movement towards and away from the turning station the gripper travels in a path which is substantially parallel with the surface of tray 37, the carrier 45 is hinged to the arm 34 at 46 and is connected by link 47 to a guide roller 48 which travels along a fixed track 49 (see Fig. 8), the roller 48 being mounted on an arm 50 hinged at 51 to arm 34. Thus as the arm 34 (and the gripper 36) swings to and fro and roller 48 travels along guide 49, link 47 is moved up and down in relation to arm 34 and the carrier 45 pivots on the end of that arm to cause the gripper to travel in the aforesaid parallel path.

Gripper 36 comprises a front jaw 36a hinged to carrier 45 for movement about an inclined axis 52, Fig. 8, such that it tends to fall open, and a rear jaw 36b mounted on a slider 53 and extending through slot 54. Slider 53 is guided on carrier 45 by means of a guide 55 and the engagement of jaw 36b with slot 54; it is movable rearwardly against the action of a return spring 56 surrounding a push rod 57 slideable in guide 55, and in order to open the gripper 36 the slider 53 has a lateral extension 53a which, when the gripper travels towards the turning station, presses against a suitably placed stop 58 (e. g. there being a stop 58 on each arm of spider 3). Jaw 36b thus opens, and jaw 36a falls forwards and downwards, so that the gripper is open to receive the toe end of the stocking. As the gripper retires, spring 56 presses against nut 59 on rod 57, so that the gripper closes on the stocking and the latter is pulled down through the tube. At a suitable stage in the retirement a pin 60 (Fig. 5) on lever 39 rocks lever 61 about pivot 62 and pushes on the end of the sheath 63 of a flexible cable 64 anchored at 65 and attached to bell crank lever 66 on arm 34. The other end of sheath 63 being anchored at 67 on arm 34, the lever 66 is thus rocked; the latter pulls on rod 57 to open the gripper 36 thereby to release the stocking. The lever 66 also pulls on curved link 68 which swings arm 69 about pivot 70 on the carrier 45, causing the end 69a of this arm to travel outwards along the gap between the two jaws 36a, 36b, to ensure the discharge of the stocking from the gripper. The stocking falls into tray 37 and as the gripper 36 next advances, the tray is swung downwards, about a hinge rod 71, to discharge the stocking. This latter movement is effected by a cam 72 acting on lever 73 (Fig. 3) which is connected by rock shaft 74, lever 75, and link 76 with the tray. The tray is drawn up again by spring 77.

In an alternative construction, the extracting mechanism is dispensed with, and the stocking is pulled out of the bottom of the hole by hand.

A counter may be provided for counting the operations of the machine. While it is readily possible to provide a counter which merely counts the number of times the plunger descends, yet such a count may not give an accurate record of the number of stockings turned, for on occasion the tubes or one of them may not be loaded. Therefore the plunger 3 may incorporate a feeler which is responsive to the presence of the stocking on the tube, and there is counting apparatus which operates only on response of this feeler. For example, the plunger may carry a pair of light contacts, which if the stocking is present on the tube are closed to complete an electrical circuit, causing the counter to operate. Alternatively, the stocking may, on being pulled clear of the bottom end of the tube, strike a trip device to operate the counter directly or through an electrical circuit.

While in the foregoing example the tubes 1a-1d are arranged to move in a circular path which is disposed in a vertical plane, the path may be disposed in any other convenient manner. For example, the tubes may travel in a circuitous path which is disposed horizontally. Moreover, while it is preferred that these tubes shall be presented substantially vertically at the loading and turning stations, yet they may be presented at these stations in any other convenient attitude. Conveyor mechanism other than that described may be employed. For example, the conveyor may

consist of a wheel or other simple rotatable member, the axis of rotation being disposed in any convenient attitude. Alternatively it may comprise an endless flexible carrier band, belt, or chain running over suitable drums, pulleys, or sprockets.

It will be appreciated that the apparatus herein described permits tubular articles to be turned inside out with facility and dispatch, but it is desirable to direct attention to two advantageous features. The fact that the stocking or the like is transported from a loading to a turning station obviates risk of injury to the operator by the plunger or other moving parts. Moreover, the fact that the operator can readily cause the apparatus to come to a standstill or cause any receiving member to pause between the loading and turning stations in the event of a stocking being incorrectly loaded minimises the risk of injury to the goods.

We claim:

1. Apparatus for turning flexible tubular objects inside out comprising, in combination, a supporting frame; two carrier members mounted on said frame rotatable in spaced planes about parallel axes; at least one link means connecting said two carrier members for rotation; at least one tubular object receiving member mounted on said link means for movement along an endless path and being adapted to have a flexible tubular object passed over it; at least one object turning member reciprocably mounted on said frame and in the plane of said path of said tubular receiving member; operating means mounted on said frame for imparting a step by step rotation to said carrier members so that said tubular receiving member pauses in the region of said turning member; reciprocating means for reciprocating said turning member between a retracted position and an advanced operative position projecting into said tubular receiving member when the same pauses in said region so as to turn an object thereon inside out; and drive means for driving said operating means and said reciprocating means.

2. Apparatus for turning flexible tubular objects inside out comprising, in combination, a supporting frame; two carrier members mounted on said frame rotatable in spaced planes about parallel axes; a plurality of link means connecting said two carrier members for rotation, each link means extending parallel to a plane passing through said axes of said carrier members and having a length equal to the distance between said axes; tubular object receiving members mounted on said link means for movement along an endless path and each being adapted to have a flexible tubular object passed over it; at least one object turning member reciprocably mounted on said frame and in the plane of said path of said tubular receiving members; operating means mounted on said frame for imparting a step by step rotation to said carrier members so that said tubular receiving members pause in the region of said turning member; reciprocating means for reciprocating said turning member between a retracted position and an advanced operative position projecting into one of said tubular receiving members when the same pauses in said region so as to turn an object thereon inside out; and drive means for driving said operating means and said reciprocating means.

3. An apparatus for turning flexible tubular objects having one end closed inside out comprising, in combination, a supporting frame;

movable supporting means mounted on said frame for movement along an endless path; a plurality of tubular object receiving members mounted on said movable supporting means for movement with the same along said endless path; a reciprocable object turning member; reciprocating means mounted on said frame and supporting said reciprocable turning member for movement along a path of reciprocating movement between a retracted position and an advanced position; 10 and drive means for moving said movable supporting means step by step along said endless path in such manner that one of said receiving members pauses in said path of said turning member when said turning member moves to said advanced position of the same, so that said turning member passes into said one receiving member for turning an object thereon, while another receiving member pauses in a position permitting placing of a flexible tubular object thereon, said 20 drive means driving said reciprocating means in a predetermined order with said movable supporting means.

4. An apparatus for turning flexible tubular objects having one end closed inside out comprising, in combination, a supporting frame; movable supporting means mounted on said frame for movement along an endless path; a plurality of tubular object receiving members mounted on said movable supporting means for movement 30 with the same along said endless path; a reciprocable object turning member; reciprocating means mounted on said frame and supporting said reciprocable turning member for movement along a path of reciprocating movement between a retracted position and an advanced position; drive means for moving said movable supporting means step by step along said endless path in such manner that one of said receiving members pauses in said path of said turning member when said turning member moves to said advanced position of the same, so that said turning member passes through and out of one end of said one receiving member for turning an object thereon, one end of said object projecting 40 out of said end of said tubular receiving member, while another receiving member pauses in a position permitting placing of a flexible tubular object thereon, said drive means driving said reciprocating means in a predetermined order with said movable supporting means; gripper means mounted on said frame movable between a retracted position and an advanced position located in the path of reciprocating movement of said turning member for engaging said end of said object; and means operated by said drive means for actuating said gripper means.

5. An apparatus according to claim 4 wherein said gripper means include jaw means, and means for opening said jaw means in said retracted position of said gripper means and for closing said jaw means in said advanced position of said gripper means.

6. An apparatus for turning flexible tubular objects having one end closed inside out comprising, in combination, a supporting frame; movable supporting means mounted on said frame for movement along an endless path; a plurality of tubular object receiving members mounted on said movable supporting means for movement with the same along said endless path; lazy-tongs means mounted on said frame movable between a collapsed and expanded position; an object turning member secured to said lazy-tongs means and moved by the same between a retracted and 70 advanced position, said turning member moving along a straight path and projecting in said advanced position thereof into said endless path of said tubular receiving member and being adapted to project into any one of said tubular receiving members for turning an object placed thereon; operating means mounted on said frame for moving said movable supporting means step by step along said endless path in such manner that one of said receiving members pauses in a receiving position in said straight path so as to be adapted to receive said turning member in said advanced position of the same, and at least another receiving member pauses in a loading position permitting placing of a flexible tubular object thereon; an actuating member mounted on said frame and connected to said lazy-tongs means for moving the same between said collapsed and expanded positions; and drive means for driving said actuating member and said operating means.

7. An apparatus for turning flexible tubular objects having one end closed inside out comprising, in combination, a supporting frame; movable supporting means mounted on said frame for movement along an endless path; a plurality of tubular object receiving members mounted on said movable supporting means for movement with the same along said endless path; lazy-tongs means mounted on said frame movable between a collapsed and expanded position; an object turning member secured to said lazy-tongs means and moved by the same between a retracted and an advanced position, said turning member moving along a straight path and projecting in said advanced position thereof into said endless path of said tubular receiving member and being adapted to project into any one of said tubular receiving members for turning an object placed thereon; operating means mounted on said frame for moving said movable supporting means step by step along said endless path in such manner that one of said receiving members pauses in a receiving position in said straight path so as to be adapted to receive said turning member in said advanced position of the same, and at least another receiving member pauses in a loading position permitting placing of a flexible tubular object thereon; an actuating member mounted on said frame and connected to said lazy-tongs means for moving the same between said collapsed and expanded positions; and drive means for driving said actuating member and said operating means.

8. An apparatus for turning flexible tubular objects having one end closed inside out comprising, in combination, a supporting frame; movable supporting means mounted on said frame for movement along an endless path; a plurality of tubular object receiving members mounted on said movable supporting means for movement with the same along said endless path; lazy-tongs means mounted on said frame movable between a collapsed and expanded position; an object turning member secured to said lazy-tongs means and moved by the same between a retracted and an advanced position, said turning member moving along a straight path and projecting in said advanced position thereof into said endless path of said tubular receiving member and being adapted to project into any one of said tubular receiving members for turning an object placed thereon; operating means mounted on said frame for moving said movable supporting means step by step along said endless path in such manner that one of said receiving members pauses in a receiving position in said straight path so as to be adapted to receive said turning member in said advanced position of the same, and at least another receiving member pauses in a loading position permitting placing of a flexible tubular object thereon; an actuating member mounted on said frame and connected to said lazy-tongs means for moving the same between a collapsed and expanded positions; and drive means for driving said actuating member, said operating means, said gripper means and said jaw actuating means in a predetermined order.

8. An apparatus as claimed in claim 6 wherein said operating means is a Geneva mechanism including a continuously rotating member, and wherein said actuating member is operatively

connected to said continuously rotating member and operated by the same.

9. An apparatus as claimed in claim 6 wherein in said movable supporting means include two carrier members mounted on said frame rotatable in spaced planes about parallel axes, and a plurality of link means connecting said two carrier members for rotation, the length of said link means being equal to the distance between said axes; and wherein said tubular receiving members are mounted on said link means.

10. An apparatus as claimed in claim 7 including an arm pivotally mounted on said frame and pivotally connected to said gripper means; a link pivotally secured at one end thereof to said gripper means; a guide roller at the other end of said link; and track means for said guide roller effecting rectilinear movement of said gripper means.

11. An apparatus for turning flexible tubular objects having one end closed inside out comprising, in combination, a supporting frame; movable supporting means mounted on said frame for movement along an endless path; a plurality of tubular object receiving members mounted on said movable supporting means for movement with the same along said endless path; lazy-tongs means mounted on said frame movable between a collapsed and expanded position; an object turning member secured to said lazy-tongs means and moved by the same between a retracted and an advanced position, said turning member moving along a straight path and projecting in said advanced position thereof into said endless path of said tubular receiving member and being adapted to project into any one of said tubular receiving members and out of one end of the same for turning an object placed thereon and for pushing an end portion of the object out of said end of said tubular receiving member; operating means mounted on said frame for moving said movable supporting means step by step along said endless path in such manner that one of said receiving members pauses in a receiving position in said straight path so as to be adapted to receive said turning member in said advanced position of the same, and at least another receiving member pauses in a loading position permitting placing of a flexible tubular object thereon; an actuating member mounted on said frame and connected to said lazy-tongs means for moving the same between said collapsed and expanded positions; an arm pivotally mounted at one end thereof on said frame; gripper means pivotally connected to the other end of said arm for movement with the same between a retracted position and an advanced position located adjacent said end of the receiving member in said receiving position of the same; a link pivotally secured at one end thereof to said gripper means; a guide roller at the other end of said link; track means

on said frame for guiding said guide roller along a straight path and effecting rectilinear movement of said gripper means during pivoting of said arm, said gripper means including movable jaw means, a fixed jaw means, and spring means urging said movable jaw means towards said fixed jaw means; a plurality of stop members on said movable supporting means, one for each receiving member, each stop member engaging consecutively said movable jaw means for opening said gripper means in the retracted position of the same, said stop members releasing said movable jaw means in said advanced position of the same; a pivoted ejector member cooperating with said gripper means; ejector actuating means including a flexible cable and connected to said ejector member; and drive means for driving said actuating member, said operating means, and said ejector actuating means, and for rocking said pivoted arm in a predetermined order.

12. An apparatus as claimed in claim 11 wherein in said operating means is a Geneva mechanism including a continually rotating member, and wherein said actuating member is operatively connected to said continuously rotating member and operated by the same, and wherein said movable supporting means include two carrier members mounted on said frame rotatable in spaced planes about parallel axes, and a plurality of link means connecting said two carrier members for rotation, the length of said link means being equal to the distance between said axes so that said link means remains substantially parallel to a plane through said axes during rotation of said carrier members; and wherein said tubular receiving members are mounted on said link means so as to remain in a substantially upright position during rotation of said carrier members.

13. An apparatus as claimed in claim 12 wherein in said frame is arranged in an upright position during operation, wherein one of said receiving members pauses in a loading position located within said frame, and another receiving member pauses in a loading position outside of and on one side of said frame, wherein said one of said receiving members pauses in said receiving position on the other side of said frame; and including a collapsible support for receiving objects released by said gripper means and located underneath the latter in said retracted position of said gripper means.

FRANK ANDREW LANDUCCI.
EDWIN IVAN RUSTED.
